UNITED STATES PATENT OFFICE.

SAMUEL R. BALL, OF OIL CITY, PENNSYLVANIA.

CONCRETE-BLOCK-MOLDING MECHANISM.

No. 829,380.

Specification of Letters Patent.

Patented Aug. 28, 1906.

Application filed October 30, 1905. Serial No. 286,016.

To all whom it may concern:

Be it known that I, SAMUEL R. BALL, a citizen of the United States, residing at Oil City, in the county of Venango and State of Pennsylvania, have invented certain new and useful Improvements in Concrete - Block-Molding Mechanism; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

This invention relates to concrete-block-molding mechanism, and has for its object the production of a molding mechanism in which the cores and the sides of the mold can be readily withdrawn from the block when the block has been molded, when the follow-board with the molded block resting thereon may be removed.

The features of this invention are herein-after set forth and explained, and illustrated in the accompanying drawings, in which—

Figure 1 is a side view in elevation of my improved mold mechanism with parts thereof broken away. Fig. 2 is a top or plan view of the same with the mold mechanism ready for filling. Fig. 3 is a side view in elevation of the side of the mold. Fig. 4 is a plan view of the mold mechanism with the sides and ends moved outward. Fig. 5 is a view in elevation of the end of the mold.

In the drawings thus illustrating this invention, A A' indicate the supporting-frame of the machine, the upper part A' of which operates as a support upon which a follow-board B rests. Within the part A' of the frame there is a vertically-movable platform or frame C, provided at its ends with upwardly-extending projections C', the tops c of which are on the same plane when raised, as illustrated in Fig. 1, as the top of the follow-board B. The parts c are also provided on their outer ends with shoulders c'. (See Fig. 1.) Secured to the vertically-movable platform or frame C are one or more core-pieces adapted to pass up through suitable openings in the follow-board B. On the upwardly-extending projections C' of the vertically-movable platform or frame C the ends of a mold E, when the mold has been opened up after the concrete block is completed, rest so that the mold E and cores D can be lowered simultaneously. The mold-box E is

made so that its ends and sides may be moved outwardly. This I preferably accomplish by pivoting on the sides and ends gear-pinions F, each of which is embraced by two yokes F', each of which has rack-gears on one side thereof, so that one rack engages the upper side and the other the lower side of the pinion F, as illustrated in Fig. 3. On the pinions F are secured operating-levers G, those on the sides being adapted to engage catches g on the sides of the mold. From the yokes F' rods F² extend to and are secured, preferably adjustably, to the sides and ends of the mold, so that the movement of the yokes F' on the sides of the mold operates to move the ends of the mold outward or inward, as desired, and the movement of the yokes on the ends of the mold operates to move the sides inward or outward, as desired. To insure the corners of the mold being right angles when the sides and ends thereof are brought together, I secure to the ends of the sides of the mold angle-pieces H and at the top and bottom thereof guide-pieces H' and to the outside of the ends of the mold plates I, which operate with the parts H and H' when the ends and sides are brought together to not only guide them to their proper positions, but to bring them exactly at right angles to each other, so that a block molded therein will be exactly square.

In the base A, I preferably mount an upright cylinder J, provided with the usual piston, (not shown,) from which a piston-rod J' extends upward and is secured to the vertically-movable platform or frame C. On the cylinder J there is a valve, preferably an ordinary four-way valve K, to which an inlet-pipe L leads and from which an exhaust-pipe L' extends, and from the upper and lower sides of the valve passages k k' extend to the upper and lower ends of the cylinder J. The valve K is provided with an operating-handle K', by means whereof the valve K can be operated to move the piston in the cylinder J, so as to raise the platform C and the open mold E, resting thereon, and the core-pieces D D, secured thereon, as shown in full lines, or lower them to the position shown by broken lines in Fig. 1, as desired.

In operation the follow-board B is placed in position on the top of the frame A', the cores D D and mold E upon the platform C raised and the sides and ends closed upon each other, when the mold E will rest entirely upon the follow-board B. The mold

may then be filled with concrete, after which the sides and ends of the mold are moved back from the block by means of the levers G on the gear-pinions F until the ends of the 5 mold E rest upon the projections C' of the platform C. The platform C can then be lowered, thereby withdrawing the cores D D from the block and lowering the open mold E below the level of the follow-board B, when 10 the follow-board B, with the finished block thereon, can be removed and another follow-board placed on the frame A', and the mechanism again operated as before.

Having thus described my invention, so as 15 to enable others to construct and operate the same, what I claim as new, and desire to secure by Letters Patent of the United States, is—

1. The combination in a concrete-block- 20 molding mechanism, of a frame, a follow-board mounted thereon, a molding-frame resting thereon, rack and gear mechanism adapted to move the sides and ends of the mold outward and inward, core-supports beneath said follow-board, cores thereon extending upward through suitable openings in said follow-board, and means for raising and lowering said core-supports, substantially as described.

25 2. The combination in a concrete-block-molding mechanism, of a mold for forming

the sides and ends of the block, pinions and rack-gears on the sides and ends thereof, connections between the racks on the sides of the mold and the ends of the mold, connections 35 between the racks on the ends of the mold with the sides of the mold, and angle-pieces on the ends of the mold adapted to contact with the sides of the mold, substantially as set forth.

3. The combination in a concrete-block-molding mechanism, of a frame, a follow-board mounted on the top thereof, a vertically-movable platform below the follow-board, extensions on the ends of said platform, a mold resting upon the extensions at the ends of said movable platform, mechanism on the sides and ends of the mold for moving the sides and ends of the mold inward and outward, a cylinder and piston in 50 the base of the machine-frame, a piston-rod extending upward to and engaging the vertically-movable platform, and valve mechanism for operating the piston in said cylinder, substantially as set forth.

55 In testimony whereof I affix my signature in presence of two witnesses.

SAMUEL R. BALL.
